US00D983487S

(12) United States Design Patent (10) Patent No.: US D983,487 S
(45) Date of Patent: * Apr. 18, 2023

(54) T-SHIRT

(71) Applicants: Yohann Tobie, Marseilles (FR); Julien Tobie, Marseilles (FR)

(72) Inventors: Yohann Tobie, Marseilles (FR); Julien Tobie, Marseilles (FR)

() Term: 15 Years

(21) Appl. No.: 35/513,308

(22) Filed: Sep. 16, 2021

(80) Hague Agreement Data

Int. Filing Date: Sep. 16, 2021

Int. Reg. No.: DM/218022

Int. Reg. Date: Sep. 16, 2021

Int. Reg. Pub. Date: Dec. 31, 2021

(51) LOC (14) Cl. 02-02

(52) U.S. Cl.

USPC D2/717
